UNITED STATES PATENT OFFICE.

CHARLES L. MILLER, OF BERKELEY, CALIFORNIA.

BALING-PRESS.

No. 800,384.

Specification of Letters Patent.

Patented Sept. 26, 1905.

Application filed January 3, 1905. Serial No. 239,339.

To all whom it may concern:

Be it known that I, CHARLES L. MILLER, a citizen of the United States, residing at Berkeley, in the county of Alameda and State of California, have invented new and useful Improvements in Baling-Presses, of which the following is a specification.

My invention relates to improvements in baling-presses, and especially that class which is designed for baling hay and like substances.

It consists in the combination and arrangement of parts and in details of construction, which will be more fully explained by reference to the accompanying drawings, in which—

Figure 1 is a side elevation of my press with follower up. Fig. 2 is a front elevation of same with follower partly down. Fig. 3 is a rear elevation of same with follower down. Fig. 4 is a plan view of eccentric wheel and direction-pulleys. Fig. 5 is a view of eccentric wheel. Fig. 6 is a view of incline. Fig. 7 is a horizontal transverse section through baling-chamber, swing movable side plate. Fig. 8 is a top plan view of power end.

My invention is especially designed to be used in that class of presses having a vertical press-box with a means for delivering charges of material into the upper part of the box, these charges being successively compressed by means of a follower which is moved downward by suitable connections, so as to compress the charges successively into the lower part of the press-box, and when the bale has been completed and tied it is removed through a door-opening which is located below the point at which the material is delivered into the press.

As shown in the drawings, A is a vertically-disposed press-box of sufficient height having a follower 2 substantially filling the interior of the box transversely, said follower having a bar with stout ends projecting through vertical slots or channels 3 in the narrow vertical sides of the press, so that levers 4 may be connected with these ends and power applied to draw the follower down after a charge has been placed within the press-box and beneath the follower. The connections for this purpose consist of lever-arms 5, having their inner ends strongly fulcrumed to the press-box, as shown at 6, and the outer ends connected with the levers 4, as shown at 7. Chains 8 connect with the ends of the levers 4, passing downwardly and inwardly therefrom to the bottom of the press, where they pass around

guide-pulleys 9, thence around direction-pulleys 10, and the two chains unite and are suitably connected with a rod 11 of sufficient length to extend to the end of the horse-power frame 12, where it is connected with a chain 13, and this chain is adapted to wind around an eccentric pulley 14.

The first downward movement of the follower and while the charge to be pressed is loose is comparatively rapid by the direct action of the chains pulling downwardly upon the levers 4; but as these levers approach the sides of the press the movement of the lever 5 in an arc about their pivot-point 6 will bring them more nearly into line with the levers 4, and this produces a compound lever action of less speed and greater power toward the end of the compression. At the same time the eccentric is in such position that its larger curvature outside of its fulcrum-shaft 15 will act, through the chain, rapidly upon the levers and follower, and as the follower approaches the bottom and the compression is nearly complete the smaller portion of the eccentric arrives beneath the chain, thus giving the greatest amount of power to compress the bale.

The upper or vertical portion A of the press is preferably hinged to the stationary base-timbers 16, as shown at 17, so that the press-box may be turned down to lie in a horizontal position for transportation, and the direction-pulleys 10 being journaled in the base-timbers will not be moved or affected by the turning down or up of the press-box.

The eccentric or power wheel has fixed to it a stop 18 in such a position that when the sweep 19, to which the team or other power is attached, arrives at a certain point during its revolution it causes the stop 18 to engage the lever 20, to which the end of the chain 13 is attached, and the further rotation of the eccentric winds the chain around said eccentric, and thus acts through its connections upon the follower, as previously described. When the compression has been completed, the end of the lever 20 rides up on an incline 21, which is in the line of movement of the lever, and the end of the lever 20 is thus raised sufficiently to disengage it from the stop 18 and allow the lever to be turned backwardly. This backward movement is effected by the engagement of a lug 22, which is carried by the sweep with a lever 23, the inner end of which is eccentrically pivoted to the frame above with the eccentric 14, as shown at 24. This engagement of the arm 22 with

the end of the lever 23 acts through a chain 25, which is connected with the lever 23, to raise the follower. The chain 25 passes around a direction-pulley 26 at the base of 5 the press-body. Thence a chain extends upwardly and at a suitable point is divided into two chains 25^a, which pass over direction-pulleys 27, and the chains 25^a pass thence down to the junction of the follower-actuating levers 10 4 and 5, so that the pull upon the chain immediately acts to raise these levers and with them the follower. As the lever 20 is now released by reason of the disengagement of said lever from the stop 18, it will be seen that 15 15 the eccentric is free to return about its pivot-post 15, and thus allow the chain 18 to unwind and the chains 8 to be extended in unison with the upward movement of the follower. As the lever 23 is eccentrically attached, as shown 20 20 at 24, the continued movement of the sweep 19 will cause the lug or hook 22 to gradually move outward beyond the end of the lever 23, so that by reason of the eccentric attachment of the lever 23 this lug 22 will be disengaged 25 25 therefrom and leave the lever and its chain connection with the follower-levers free to move in unison with the movements of the follower, when the latter is again depressed. In this manner the follower is alternately 30 30 drawn down by the power communicated through the sweep to the eccentric 14 and is released and again raised to allow another charge to be placed beneath it.

The incline 21 is pivoted or otherwise made 35 conveniently movable, so that when the last charge to complete the bale has been placed in the press this incline may be swung out of line of the lever 20, and the latter not then being raised and disengaged it will be seen 40 40 that the follower will be held down by the power applied to the sweep and can remain in this position until the cords or wires by which the bale is secured have been passed around the bale and tied. Then the lever 20 45 45 may be raised by a hand-bar or otherwise and the parts disengaged. The incline 21 being swung back to its normal position, the parts will be in readiness to press another bale.

The successive charges of material which 50 50 are compressed by the descent of the follower are prevented from again rising by the usual hinged retainers, which consist of bell-crank latches 28, pivoted so that their points project into the interior of the press. These latches 55 55 are freely movable in one direction to allow the material to pass downwardly, but are weighted or otherwise arranged to return and project above the material as soon as it has passed and to hold it in place while the follower is again being raised.

In order to discharge a completed bale, a door, as 29, is hinged upon the side of the press-box opposite the position of the compressed bale and is held in its closed position 60 65 by means of a swinging bar 30, hinged to the

side of the press and adapted to pass over the outer end of the door after it is closed.

In order to free the bale and allow it to be easily removed from the press-box, I have shown the following arrangement: It is desirable that the bale should be rectangular, and for this three sides of the press-box provide. The other side 31 is beveled or inclined so that the space is wider next the door than toward the opposite side. Across this 70 75 space is a heavy piece of boiler-plate 32, one edge of which is pivoted or loosely held, as at 32', in the side of the press opposite the door-opening. The door carries an edge plate, as at 33, contiguous to its hinge 34, and this 80 edge plate passes beneath or behind the plate 32 when the door is closed, and this holds the plate 32 substantially at right angles with the sides of the press-box and forms a rectangular chamber for the bale. As soon as the 85 door is opened the removal of the plate 33 from beneath the plate 32 allows the latter to swing and lie against the inclined side 31, so that the pressure upon the bale will be relieved sufficiently to allow it to be withdrawn 90 from the press.

The material may be supplied to the press by means of a hay-fork and derrick or other device, through the aid of which the material may be deposited upon a platform 36, conveniently disposed with relation to the door 37, through which the supply is delivered into the press-box. This door is hinged at the bottom, as at 38, and its upper outer edge is thus allowed to turn in a quadrant, so that it opens outwardly and downwardly, and the charge may be delivered into the press through the opening which the door serves to close. When the charge has been placed in the press, the door is closed by a pull 100 upon the chains 39. These chains have one end connected with the door near the movable edge. They pass thence around guide-pulleys at 40, which are located in such position with relation to the door that the pull upon the chain will be substantially at 105 right angles with the movement of the door. Thus the door may be closed against any pressure of the material which is contained 110 within the press-box. From the pulley 40 a chain leads over a pulley 41, journaled on the follower, so that the upward movement of the follower will pull the chain and close the door, and its downward movement will slacken the chains and release the door.

41^a is an attachment for the end of the chain and is movable up or down to insure the proper closing of the door.

43 is a latch or latches fulcrumed so as to engage the edge of the door when it is fully closed. These latches are pressed downwardly by springs 44, so that they will automatically engage the door when closed. In order to open these latches, they have arms projecting from opposite sides of the fulcrum- 125 130

point 45, and to these arms are connected chains 46. The lower ends of these chains are connected with levers, as 47, which project into the line of the slot or channel 3, in which the follower ends move, so that as the follower moves downward to compress the charge which is within this portion of the press it engages and pulls upon the levers 47, thus tilting the latch and releasing the door 37, 10 which can immediately fall outward and be ready for another charge, while the follower continues its downward motion to complete the compression of the charge.

The plate 33 is securely bolted to the door 29 and moves with it, so that the opening or closing of the door will move the plate 32 automatically and without other care or attention.

Having thus described my invention, what 20 I claim, and desire to secure by Letters Patent, is—

1. In a baling-press, a substantially rectangular press-box having one side inclined outwardly toward the discharge-door opening, a 25 plate movable with relation to said inclined side so as to complete the rectangular interior, and means by which said plate is permitted to retract to relieve pressure upon the bale and allow it to be discharged.

2. In a baling-press, a vertically-disposed box made substantially rectangular in the upper part having a follower movable therein, said box having a portion of one side inclined outwardly toward the discharge-opening for 35 the bale, a plate swiveled at one edge and movable into contact with the inclined surface to relieve pressure upon the finished bale, a swinging door adapted to close the discharge-opening, and a plate carried by said door and adapted to move the swinging plate to stand 40 substantially at right angles with the side of the box opposite the door while the door is closed.

3. In a baling-press, means for forming a 45 substantially rectangular bale in the compression-chamber of the box, said means comprising a plate turnable about the vertical edge which is opposite to the discharge-door of the press, a stop carried by the door to press 50 against the free edge of the swinging plate and maintain it in position when the door is closed, said stop being removed when the door is opened to allow the plate to swing outwardly and relieve pressure upon the bale.

55 4. In a baling-press, a vertically-disposed press-box having a feed opening and door in the upper part, a discharge-door in the lower part, said press-box having one side inclined outwardly toward the discharge-door and a 60 plate movable with relation to said inclined side so as to complete the rectangular interior and means by which said plate is permitted to retract to relieve the pressure upon the bale, a reciprocating follower, levers having 65 the inner ends pivoted to the said follower,

other levers pivoted to the press-box having their outer ends connected with the first-named levers at points between opposite ends thereof, chains connecting with the outer or short arms of said first-named levers, direction-pulleys at the base of the press around which said chains pass, an eccentric pulley and a chain connection from the follower passing around said pulley, a sweep through which power is transmitted to rotate the eccentric 75 and move the follower, and a mechanism by which the eccentric is released at the end of the follower-stroke.

5. In a baling-press, a vertically-disposed press-chamber having a feed-door in the upper part, a discharge-door below, means in the compression-chamber allowing said chamber to expand to relieve the pressure upon the bale coördinately with the opening of the discharge-door, a follower movable in said 80 box, levers connected with said follower, chains connecting with the outer ends of the levers, direction-pulleys around which said chains pass to a point of union, an eccentric, a chain passing around said eccentric, connecting with the follower-chains, a sweep through which power is applied, a lever to which the end of the chain passing around the eccentric is connected, a lug carried by the eccentric 85 connected to contact with said lever and thus wind up the chain, and an incline by which the lever is raised and disengaged from the lug at the termination of the downward movement of the follower.

6. In a baling-press, a press-box, a follower, 100 levers and chains by which the follower is moved to compress a charge, an eccentric, a sweep through which power is applied to rotate the eccentric, a chain connected with the follower-chains, passing around the eccentric, 105 a lever turnable about the eccentric-shaft to which the end of the chain is attached, a lug carried by the eccentric adapted to engage the lever and move it in unison with the movements of the eccentric, an incline adapted to 110 raise the end of the lever and disengage it from the lug at the termination of the follower movement, said incline being pivoted so as to be turned out of the path of movement of the lever.

7. In a baling-press, a press-box, a follower movable therein, levers connected with the follower, chains connected with the ends of the levers, direction-pulleys at the base of the press around which the chains pass to unite 120 in a single pulling device, an eccentric, a sweep through which power is applied to revolve the eccentric, a chain connection with the follower-chains passing around the eccentric, a lever turnable upon the eccentric-shaft with 125 which lever the pulling-chain is connected, a lug carried by the eccentric adapted to engage the lever and wind the chain about the eccentric, a disengaging device to release the chain-carrying lever from the lug, a lever fulcrumed 130

- to turn in a plane substantially parallel with that of the sweep, a lug projecting from the sweep and engaging said lever after the chain-lever has been disengaged from the eccentric-lever 5 and a chain connection whereby the continued movement of the sweep returns the follower and its levers to their normal position.
8. In a baling-press, a follower, levers and chain connections by which said follower is moved to compress a charge, an eccentric around which the chain connection from the follower passes, a lever turnable about the eccentric-shaft with which lever the pulling-chain is connected, means engaging the eccentric with said lever to wind the chain and move the follower, a disengaging device to allow the chain to be retracted, a sweep through which power is applied to revolve the eccentric, an arm fulcrumed eccentrically to the shaft about which the sweep turns, said arm having return-chains connecting it with the follower-actuating levers, a lug carried by the sweep and engaging the end of said arm after the chain-pulling lever has been released, said lug being disengaged from the arm by reason of the eccentricity of its movement.
9. In a baling-press, a vertically-disposed press-box having means in the compression-chamber allowing said chamber to expand to relieve the pressure upon the bale substantially coördinately with the delivery of the bale, a follower movable in said box, fulcrumed lever-arms and chains connecting said arms with a power mechanism by which the follower is moved to compress the charge, mechanism actuated by the power-sweep, whereby the follower-chains are caused to pull the follower down, a releasing mechanism for said pulling device, return-chains connecting with the follower-levers, and mechanism actuated by the continued movement of the power-sweep to engage said chains and return the follower.
10. In a baling-press, a fixed base, a vertically-disposed baling-chamber, a hinge by which said chamber is turnably connected with the base, a follower movable in the press-box, fulcrumed levers and chain connections with a power mechanism, direction-pulleys around which said chains pass from the levers of the power mechanism, said pulleys being located in the fixed base, whereby the press-box may be turned into a horizontal position without deranging the chain connections.
11. In a baling-press, a vertically-disposed

press-box, having a feed-door in the upper part and a bale-discharge door in the lower part, said box having one side inclined outwardly toward the discharge-door opening, a member in the box to complete the rectangular chamber thereof, and means by which said member is permitted to retract substantially coördinately with the opening of the discharge-door whereby the pressure upon the bale is relieved, a follower, fulcrumed levers connected with the follower, chains connecting said levers with the power mechanism, latch-levers adapted to retain the feed-door in closed position, other levers projecting into the path of movement of the follower near the termination of its compressing movement, and chains connecting said levers with the latch-levers whereby the feed-door is automatically released during the compression of the charge.

12. In a baling-press, a press-box, a follower and mechanism by which it is reciprocated within the box, a feed-opening and a door hinged at its lower edge, chains having one end connected with the door and the other ends to points upon the press, and intermediate pulleys journaled upon the follower and acting on the chains to close the door.

13. In a baling-press, a press-box, a follower and mechanism by which it is reciprocated in the box, a feed-opening and a door hinged at its lower edge, chains with adjustable attachments for one end upon the press-box, and attachments on the door for the opposite ends, pulleys on the follower engaging the bights of the chains and acting to close the door, and direction-pulleys upon the box whereby the vertical movement of the follower is converted into a substantially horizontal movement of the chains to close the door.

14. In a baling-press, a press-box with an inclined cut-away side contiguous to the discharge-door, a plate loosely fitting said cut-away section, and stops fixed to and swinging with the door, by which the plate is automatically moved forward or released by the closing or opening of the door.

In testimony whereof I have hereunto set my hand in presence of two subscribing witnesses.

CHARLES L. MILLER.
